UNITED STATES PATENT OFFICE.

WILLIAM SPARKS, OF JACKSON, MICHIGAN, ASSIGNOR TO THE SPARKS-WITHINGTON COMPANY, OF CLEVELAND, OHIO, A CORPORATION OF OHIO.

SIGNALING DEVICE.

Application filed August 18, 1921. Serial No. 493,498.

This invention relates to certain new and useful improvements in signaling devices, and is closely related to my co-pending application, Serial No. 396,802, filed July 16, 5 1920.

The main object of the invention is the production of a signaling device of the motor driven type, in which accurate adjustment to a substantially predetermined extent 10 is readily made, either to compensate for wear or to effect the desired positioning of the diaphragm-actuating member with reference to the diaphragm to produce such vibration of the latter as will result in the production of a satisfactory signal for the purpose at hand.

Another object is the production of a signaling device having the adjustment advantages above described, in which the parts are 20 normally so held in any position of adjustment as to prevent rattling of the same under ordinary conditions of use.

Other objects and advantages relate to the details of construction, form and arrangement of the said parts by which the above set forth objects are attained, all as will more fully appear from the following description, taken in connection with the accompanying drawings, in which:

30 Figure 1 is a longitudinal section through a device of my invention.

Figure 2 is a rear end elevation of the same, with the cover removed.

Figure 3 is a fragmentary view showing 35 the corrugated strap.

Figure 4 is a sectional view on line 4—4, Figure 3.

Figure 5 is a view similar to Figure 4 showing the adjusting nut in position.

40 Figure 6 is an enlarged sectional view similar to the section of Figure 1 illustrating the mechanism for moving the armature shaft toward the diaphragm.

Figure 7 is a section on line 7—7, Figure 2.

45 Figure 8 is an end view of the adjusting bar.

The signal shown, comprises a resonator 1—, a front diaphragm case section 2—, a diaphragm 3—, a rear diaphragm case section 4— formed with a pair of spaced openings for the reception of the respective

threaded end portions 5— and 6— of a U-shaped motor case or yoke 7—, the nuts 8— engaging the threaded ends of the case 7— to rigidly connect the same to the rear 55 diaphragm case section 4—.

The motor case 7— carries the usual pole pieces 9—, field coils 10—, and commutator brushes 11—. The armature 12— of the motor is mounted upon the armature shaft 13—, which shaft has one end extending through the rear wall 14— of the motor case, and its opposite end extending through and journaled in the rear diaphragm case section 4—. The armature 60 shaft carries at a point forward of the case section 4—, a cam or toothed member 15— adapted to contact with a projection 16— upon the central portion of the diaphragm to effect vibration of the latter upon 65 rotation of the cam. The cam may be held upon the armature shaft in any suitable way, as by means of a nut 17—.

The brushes 11— are adapted to contact with commutator 19— upon the armature 75 shaft.

For the purpose of effecting desired adjustment of the armature shaft, to vary the relative position of the cam 15— and the projection 16— upon the diaphragm to produce the desired vibration of the latter, I have provided an end thrust bearing consisting of a bar 20— extending substantially parallel with the rear wall 14— of the U-shaped motor shell, and having one end 21— bent 80 at substantially right angles to the body of the bar and formed with a reduced portion 21— through an opening in the rear wall 14— so as to slide therein, but limit movement in the direction of length of the bar. 90 Preferably, as shown, the bar 20— is of channel form and has one of its ends formed with a depressed portion 18— adapted to receive and retain one end of a spring 22— positioned between the free end of the bar and the rear wall 14—. Preferably the spring 95 is disposed on the opposite side of the shaft 13— from the flanged end 21— that extends through the wall 14—.

Intermediate the spring and the flanged end 21— the shaft 13— bears against the bar 20— and for the purpose of moving the 100

bar towards the wall —14— I have provided a threaded stud —23— adapted to have an adjustable threaded engagement with the rear wall —14— and extend through the bar —20—. This stud comprises an enlarged head portion —24— preferably provided with a slot for the reception of rotating means.

In order to effect predetermined fine degrees of adjustment I have provided a strap —26— which extends across the bar —20— and has its ends —27— and —28— bent at substantially right angles to its laterally extending portion so as to lie in substantial contact with the edges of the bar —20—. The upper portion of this strap, or adjusting member, is provided with a series of radially extending grooves or notches —40— adapted to conform with and receive a series of projections —30— upon the lower face of the enlarged head —24— of stud —23—. By forming these receiving grooves and projecting parts of desired size, any predetermined quantity of adjustment may be effected by moving the stud —23— through a single notch or additional notches should further adjustment be desired.

Further, this interlocking engagement of the parts holds them rigidly in any predetermined position of adjustment. In order to prevent forward movement of shaft —13— and to hold it in comparatively rigid position to prevent rattling during use, I have provided a spring member —31— as shown in the form of an elongated plate, having an intermediate bend, one end of which spring bar or plate is mounted on the threaded end —5— of the motor case at the rear of the butt —8—, the opposite end of said bar contacting with the front end of the armature shaft —13—, the spring bar being so tensioned as to exert a thrust force upon the said shaft, tending to hold it in contact with the bar —20— at the rear of the case.

Preferably, as shown, the rear wall —14— of the case —7— is provided with a recess —32— for receiving the inner end of the spring —22—, the outer end of which surrounds the boss 18—.

It will be understood from the above description that very accurate adjustment can be made by this structure, and the parts can be rigidly held in any predetermined position of adjustment without rattling, and that the adjustment is effected easily and efficiently upon the exterior of the cup-shaped case —35— through which the head —24— of the stud —23— is adapted to project as best shown in Figure 1.

Although I have shown and described a specific construction as illustrative of a perhaps preferred embodiment of my invention, I do not desire to limit myself to the details of construction of the same, as various changes and modifications may be made with-

out departing from the invention as set forth in the appended claims.

I claim:

1. An apparatus of the character described comprising a diaphragm having a wear-piece thereon, an armature shaft presented endwise toward the diaphragm and having a rotor upon its forward end for contact with said wear-piece, a case in which the rear portion of said armature shaft is journaled, a rigid cross-bar at the rear of the case and having a portion bearing against but unconnected to the adjacent end of the armature shaft, spring means urging said shaft into contact with said cross-bar and a stud extending through said cross bar and having a threaded engagement with said case for adjusting said cross-bar toward the case.

2. An apparatus of the character described comprising a diaphragm having a wear-piece thereon, an armature shaft presented endwise toward the diaphragm and having a rotor upon its forward end for contact with said wear-piece, a case section in which the rear portion of said armature shaft is journaled, a rigid cross-bar at the rear of the case section and having a portion bearing against but unconnected to the adjacent end of the armature shaft, spring means urging said shaft into contact with said cross-bar and a stud engaging the cross-bar at one side of the armature shaft and adjustable with respect to the case section for adjusting the said cross-bar toward the case-section to thereby adjust the armature shaft and rotor with respect to said wear-piece.

3. An apparatus of the character described comprising a diaphragm having a wear-piece thereon, an armature shaft presented endwise toward the diaphragm and having a rotor upon its forward end for contact with said wear-piece, a case-section in which the rear portion of said armature shaft is journaled, a rigid cross-bar at the rear of the case-section and having a portion bearing against but unconnected to the adjacent end of the armature shaft, spring means urging said shaft into contact with said cross-bar, a stud engaging the cross-bar at one side of the armature shaft and adjustable with respect to the case-section for adjusting the said cross-bar toward the case-section to thereby adjust the armature shaft and rotor with respect to said wear-piece, and a casing enclosing the case-section, and having an opening through which the end of said stud extends to permit adjustment of said cross-bar without removing the casing.

4. An apparatus of the character described comprising a diaphragm having a wear-piece thereon, an armature shaft presented endwise toward the diaphragm and having a rotor upon its forward end for contact with said wear-piece, a case-section in which the rear portion of said armature shaft is journaled, a rigid cross-bar at the rear of the case-section

and having a portion bearing against but unconnected to the adjacent end of the armature shaft, spring means urging said shaft into contact with said cross-bar, a stud engaging the cross-bar at one side of the armature shaft and adjustable with respect to the case-section for adjusting the said cross-bar toward the case-section to thereby adjust the armature shaft and rotor with respect to said 10 wear-piece, a casing enclosing the case-section, and having an opening through which the end of said stud extends to permit adjustment of said cross-bar without removing the casing, and additional means connected to the cross-bar and engaging the case section for guiding the cross-bar in its movement toward the case-section.

5. The combination with a cross wall provided with a pair of openings, of a shaft journaled in one of said openings, a cross bar extending substantially parallel with the cross wall and having a flange positioned in the other opening in the cross wall, means for moving said cross bar towards the cross wall 20 to position said shaft, and spring means tending to move said cross bar away from the cross wall.

6. In a structure of the character described, a case section, a U-shaped case secured to said case section, a shaft journaled in said case section and the rear wall of the U-shaped case, a rigid cross-bar at the rear of the U-shaped case having a portion in contact with but unconnected to the adjacent end of the motor shaft, a headed stud engaging said cross bar at one side of said shaft and having an adjustable relation with the U-shaped case, and a cover extending over the U-shaped case and having an opening through which the head 30 of said stud is exposed.

7. An apparatus of the character described comprising a diaphragm having a wear-piece thereon, an armature shaft presented endwise toward the diaphragm and having a rotor upon its forward end for contact with said wear-piece, a case in which the rear portion of said armature shaft is journaled, a cross-bar at the rear of the case and having a portion bearing against the adjacent end of the armature shaft, a stud extending through said cross bar and having a threaded engagement with said case for adjusting said cross-bar toward the case, and additional means for spacing the cross bar from the case.

55 8. An apparatus of the character described, comprising a diaphragm having a wear-piece thereon, an armature shaft, a rotor mounted on the front end of said armature shaft for engagement with said wear-piece, a case section in which the rear portion of said armature shaft is journaled, and means for adjusting said armature shaft toward the diaphragm to vary the over-lap of said rotor on said wear-piece comprising a cross bar at the rear of the case section, and having a

portion contacting with the rear end of the armature shaft, and a flanged portion engaged with the case section, a threaded member extending through the cross-bar at one side of the armature shaft and having a 70 threaded engagement with the case section, and a spring disposed upon the opposite side of the armature shaft from said member and positioned between the case section and the cross bar. 75

9. In an end thrust bearing for shafts, a cross wall, a shaft journaled in said cross-wall, said cross-wall provided with an opening, a cross-bar extending substantially parallel with said cross wall and having a flanged 80 portion positioned in said opening, a stud engaging said cross-bar upon one side of one shaft and having an adjustable engagement with said cross-wall, and spring means upon the opposite side of said shaft disposed between the cross-wall and the cross-bar for spacing the cross bar from the cross wall. 85

10. In an end thrust bearing for shafts, a cross-wall, a shaft journaled in said cross-wall, said cross-wall provided with an opening, a cross-bar extending substantially parallel with said cross-wall and having a flanged portion positioned in said opening, a stud engaging said cross-bar upon one side of one shaft and having an adjustable engagement 90 with said cross-wall, spring means upon the opposite side of said shaft disposed between the cross-wall and the cross-bar for spacing the cross bar from the cross wall, and a resilient member for normally holding said 95 member in contact with said cross-bar. 100

11. An apparatus of the character described comprising a diaphragm having a wear-piece thereon, an armature shaft, a rotor mounted on the front end of said armature shaft for engagement with said wear-piece, a case section in which the rear portion of said armature shaft is journaled, means for adjusting said armature shaft toward the diaphragm to vary the over-lap 105 of said rotor on said wear-piece comprising a cross bar at the rear of the case section and having a portion contacting with the rear end of the armature shaft, and a flanged portion engaged with the case section, a threaded member extending through the cross-bar at 110 one side of the armature shaft and having a threaded engagement with the case section, a spring disposed upon the opposite side of the armature shaft from said member and positioned between the case section and the cross bar, and a casing enclosing the case section and having an opening through which the end of said threaded member extends. 115 120

12. An apparatus of the character described comprising a diaphragm having a wear-piece thereon, an armature shaft, a rotor mounted on the front end of said armature shaft for engagement with said wear-piece, a case section in which the rear portion 125

of said armature shaft is journaled, means for adjusting said armature shaft toward the diaphragm to vary the over-lap of said rotor on said wear-piece comprising a cross-bar at the rear of the case section and having a portion contacting with the rear end of the armature shaft, and a flanged portion engaged with the case section, a threaded member extending through the cross-bar at one side of the armature shaft and having a threaded engagement with the case section, a spring disposed upon the opposite side of the armature shaft from said member and positioned between the case section and the cross-bar, a casing enclosing the case section and having an opening through which the end of said threaded member extends, said threaded member having a toothed surface, and means interlocking with said toothed surface for frictionally holding the threaded member in any predetermined position while permitting a step-by-step adjustment for varying the overlap of said cam upon said wear-piece.

13. An apparatus of the character described comprising a case part, a diaphragm having a wear-piece thereon, a rotary armature shaft presented endwise toward the diaphragm and journaled in said case part and having a rotor upon its forward end for engagement with said wear-piece, a rigid cross-bar at the rear of the case part and having one end connected to the case part at one side of the armature shaft in a manner to prevent endwise movement of said bar and having its opposite end extending across the armature shaft at the rear end thereof and unconnected to said shaft, spring means urging said shaft rearwardly, and a rotary screw member extending through said cross-bar, and rotatable with respect to the cross-bar for adjusting said shaft endwise to vary the overlap of said rotor upon said wear-piece upon rotation of said screw member.

14. A structure of the character described comprising a shaft, an end-thrust bearing for the shaft comprising a rotatable member and a toothed surface carried by said member, means engaging the said toothed surface for frictionally locking the rotatable member in any position of adjustment while permitting a step by step adjustment of a predetermined amount, and a casing enclosing said elements and having an opening through which the end of the rotatable member extends, and permitting adjustment of said shaft without removing the casing.

15. A structure of the character described comprising a case part, a shaft journaled in said case part, an end thrust bearing for the shaft comprising a rotatable member having an adjustable engagement with said case part, a toothed surface carried by said member, and means engaging the toothed surface for frictionally holding the rotatable member in any position of adjustment, but per-

mitting a step by step adjustment of a predetermined amount, and a casing enclosing said elements and having an opening through which the rotatable member extends and permitting adjustment of said shaft without removing the casing.

16. An apparatus of the character described comprising a diaphragm having a wear-piece thereon, an armature shaft, a rotor mounted on the front end of said armature shaft for engagement with said wear-piece, a case section in which the rear portion of said armature shaft is journaled, means for adjusting said armature shaft toward the diaphragm to vary the over-lap of said rotor on said wear-piece comprising a rotatable member having a toothed surface rotating with said member, and means engaging the said toothed surface for frictionally locking the rotatable member in any position of adjustment while permitting a step-by-step adjustment of a predetermined amount to thereby vary the over-lap of said cam upon said wear-piece.

17. An apparatus of the character described comprising a diaphragm having a wear-piece thereon, an armature shaft, a rotor mounted on the front end of said armature shaft for engagement with said wear-piece, a case section in which the rear portion of said armature shaft is journaled, means for adjusting said armature shaft toward the diaphragm to vary the over-lap of said rotor on said wear-piece comprising a rotatable member having a toothed surface rotating with said member, and means engaging the said toothed surface for frictionally locking the rotatable member in any position of adjustment while permitting a step-by-step adjustment of a predetermined amount to thereby vary the over-lap of said cam upon said wear-piece, and a casing enclosing the said case section and having an opening through which the end of the rotatable member extends to thereby permit adjustment of said shaft without removing the casing.

18. An apparatus of the character described comprising a diaphragm having a wear-piece thereon, an armature shaft, a rotor mounted on the front end of said armature shaft for engagement with said wear-piece, a case section in which the rear portion of said armature shaft is journaled, means for adjusting said armature shaft toward the diaphragm to vary the over-lap of said rotor on said wear-piece comprising a cross-bar at the rear of the case section and having a portion contacting with the rear end of the armature shaft and a flanged portion engaged with the case section, a threaded member extending through the cross-bar at one side of the armature shaft and having a threaded engagement with the case section, a spring disposed upon

the opposite side of the armature shaft from said member and positioned between the case section and the cross-bar, a casing enclosing the case section and having an opening 5 through which the end of said threaded member extends, said threaded member having a toothed surface, means interlocking with said toothed surface for frictionally holding the threaded member in any predetermined 10 position while permitting a step-by-step adjustment for varying the overlap of said cam upon said wear-piece, and means engaging the end of the shaft between the cam and the diaphragm for resiliently holding said shaft in contact with said cross-bar.

19. An apparatus of the character described comprising a diaphragm having a wear-piece thereon, an armature shaft, a rotor mounted on the front end of said armature shaft for engagement with said wear-piece, a case section in which the rear portion of said armature shaft is journaled, means for adjusting said armature shaft toward the diaphragm to vary the over-lap of said rotor on said wear-piece comprising a rotatable member having a toothed surface rotating with said member, means engaging the said toothed surface for frictionally locking the rotatable member in any position of adjustment while permitting a step-by-step adjustment of a predetermined amount to thereby vary the over-lap of said cam upon said wear-piece, and means engaging the end of the shaft between the cam and the diaphragm for resiliently holding said shaft in contact with said cross-bar.

20. An apparatus of the character described comprising a diaphragm having a wear-piece thereon, an armature shaft presented endwise toward the diaphragm and having a rotor upon its forward end for contact with said wear-piece, a transversely extending case-portion having a bearing in which the rear portion of said shaft is journaled, and through which the rear portion

of said shaft extends, a rigid cross-bar at the rear of said transverse case portion, said bar having a portion engaged with the case portion at one side of said shaft and another portion extending across the end of the shaft and unconnected to the shaft, adjustable screw means engaging the said cross-bar and adapted to effect endwise adjustment of said shaft with respect to the case 55 section to vary the over-lap of the rotor upon said wear-piece, spring means urging said shaft rearwardly and a casing enclosing the case portion and cross-bar and having an opening through which a portion of the adjustable screw means extends to permit adjustment of said shaft by rotation of said screw means without removing the casing.

21. A signal, including a diaphragm, means for mounting the same, a driving 65 shaft, a diaphragm-actuating mechanism, one of the elements thereof being secured to said shaft and another to said diaphragm, a frame through which said shaft extends, a rigid bar located slidably at the rear of said frame and providing an unyielding end-thrust bearing for said shaft, and a member adjustably connecting the bar and frame to vary the degree of cooperation of the parts of the diaphragm-actuating mechanism. 70

22. A signal, including a diaphragm, means for mounting the same, a driving shaft, a diaphragm-actuating mechanism, one of the elements thereof being secured to said shaft and another to said diaphragm, so a frame through which said shaft extends, a bar providing a bearing for said shaft, a member adjustably connecting the bar and frame to vary the degree of cooperation of the parts of the diaphragm-actuating mechanism, and means adjacent said member and cooperating with said bar to retain the latter in proper engagement with said member. 75

In witness whereof I have hereunto set 90 my hand this 30th day of July, 1921.

WILLIAM SPARKS.
